UNITED STATES PATENT OFFICE.

JAMES E. JACKSON, OF LYNN, MASSACHUSETTS, ASSIGNOR TO UNITED-XPEDITE FINISHING COMPANY, OF BERWICK, MAINE, A CORPORATION OF MAINE.

HEEL-FINISHING MACHINE.

No. 824,931.

Specification of Letters Patent.

Patented July 3, 1906.

Application filed May 26, 1905. Serial No. 262,441.

To all whom it may concern:

Be it known that I, JAMES E. JACKSON, of Lynn, in the county of Essex and State of Massachusetts, have invented certain new and useful Improvements in Heel-Finishing Machines, of which the following is a specification.

This invention relates to machines for producing a smooth polished surface on leather articles, such as boot and shoe heels, by the employment of wax and suitable frictional rubbing pressure, the wax being softened by heat when applied.

The invention has for its chief object to provide improved means for frictionally heating and distributing finishing or burnishing wax without the employment of a burner and for applying the wax to a heel.

The invention also has for its object to provide a heel-finishing machine having various improvements looking to the effectiveness and convenience of its operation.

The invention consists in the improvements, which I will now proceed to describe and claim.

Of the accompanying drawings, Figure 1 represents a front elevation of a heel-finishing machine embodying my invention. Fig. 2 represents an end elevation of the same looking toward the left-hand end, as viewed in Fig. 1. Fig. 3 represents a section on line 3 3 of Fig. 1. Fig. 4 represents a perspective view of the frictional wax heating and distributing member. Fig. 5 represents a section on line 5 5 of Fig. 4.

The same reference characters indicate the same parts in all the figures.

In the drawings, 12 represents the supporting-frame of the machine, said frame having bearings 13 13, in which is journaled a shaft 14, supporting the various rotary members, hereinafter described, for finishing a heel. The shaft is also provided with fast and loose pulleys or other means for applying power to the shaft and for stopping its rotation.

15 represents a roll affixed to the shaft 14, the said roll being preferably composed of a rigid central portion 1 and a yielding peripheral portion 2, of felt or other suitable yielding material.

17 represents an endless wax-carrier, which is preferably composed of textile fabric,

the best material known to me being stout webbing, this material presenting numerous pockets in its surface adapted to engage and carry wax and being adapted by its softness and lack of abrasiveness to impart a polish to a smooth surface by aid of the wax. This carrier is preferably made in the form of a belt, which is of suitable length to run upon the roll 15 and upon an idle roll or pulley 18, mounted on a shaft 19, which is located behind and is parallel with the shaft 14. When the machine is in operation, the operator applies ordinary burnishing-wax to the carrier 17, preferably at a point below the roll 15, the latter rotating in the direction indicated by the arrow in Fig. 2. The rotation of the roll causes the carrier 17 to carry the wax around to the upper and front portions of the roll 15. The heel to be acted on is applied to that portion of the carrier 17 which is supported by the front portion of the roll 15—namely, the portion at the right, as shown in Fig. 2.

20 represents a frictional wax heating and distributing shoe, which is in rubbing contact with the wax-carrier and is located above the roll 15, as shown in Fig. 2, said shoe being preferably composed of a metal back 3 and metal ears 4 4, formed thereon, a yielding cushion 5, of material such as felt, and a frictional face 6, preferably of sole-leather, the flesh side of which is cemented to the cushion 5, while the grain side bears on the wax-carrier. The function of the shoe 20 is to frictionally heat the wax applied to the carrier 17 and spread and distribute the wax, thus causing the application of a uniform film or coating of wax to the heel. The shoe 20 is supported by a holder 21, adjustably mounted, as hereinafter described, on the frame of the machine, the said shoe having a shank 22, provided with an ear at its outer end, which is pivoted at 23 to the holder 21. Means are provided for varying the pressure of the shoe 20 upon the carrier 17, so that the pressure can be adjusted to varying conditions of temperature, hardness of the wax employed, &c. As here shown, the said means comprise an arm 24, formed on or affixed to the holder 21, said arm projecting over the shank 22, and an adjusting-screw 25 adjustably engaged with the arm 24 and bearing on the shank 22.

The face 6 of the shoe 20 is shaped to conform closely to the transverse contour of the wax-carrier 17, said contour being preferably curved, as shown in Fig. 1. The shoe, therefore, heats the wax uniformly across the carrier 17 and reduces it to a uniform film or coating, a portion of which is pressed into the interstices of the fabric of the carrier 17. The result is the application of a uniform film or coating of heated wax to the heel presented to the portion of the carrier 17 that is supported by the roll 15, the wax being heated wholly by friction and without the use of gas-burners.

15 The idle pulley 18, on which the carrier 17 runs, is affixed to a shaft 19, which is journaled in a bearing formed in a movable support 26, which has a dovetailed base 27 fitted to slide between guides 28 on an arm 29, engaged with the supporting-frame and projecting rearwardly therefrom. The support 26 is therefore adjustable toward and from the operating-shaft 14 to provide for the regulation of the tension of the belt-shaped carrier 17. The support 26 may be secured at any position to which it may be adjusted by means of an adjusting-screw 30, engaged with the support 26 and with an ear 31 on the arm 29.

30 The arm 29, supporting the support 26, is preferably adjustably secured to the frame of the machine by means of a horizontal trunnion 32, Fig. 3, adapted to turn in a horizontal socket 33 in the supporting-frame. A clamping or locking screw 34, engaged with the trunnion 32 and bearing on a shoulder formed in the socket 33, co-operates with a flange or shoulder 35 on the arm 29 in clamping the arm to the supporting-frame in any position to which it may be adjusted by the turning of the trunnion 32 in its socket. The object of this adjustment is to secure the parallelism of the shaft 19 with the shaft 15, and thus prevent liability of the untrue running of the carrier 17.

The shoe-holder 21 is preferably affixed to the bracket 26 and supported thereby, as shown in Fig. 2.

50 The shaft 14 is here shown as provided with additional heel-finishing appliances comprising a roll 37, which is preferably coated with felt, a brush 38, and a beading-wheel 39. After the heel has been subjected to the wax-carrier 17 it is subjected successively to the action of the roll 37, brush 38, and wheel 39, or this order may be changed as circumstances may require.

55 The bearings 13 of the shaft 14 are supported by arms 40, which project forward from the supporting-frame 12, so that the shaft overhangs a space below it. The arms 40 are provided at their inner ends with vertical studs or trunnions 41, which are adapted to turn horizontally in sockets 42 in the supporting-frame and are secured to said socket-

60 by set-screws 43. This construction permits a swinging adjustment of the bearings 13, or either of them, to secure their perfect alignment.

The acting face 6 of the shoe may be removed from the cushion 5 when worn and another face substituted for it. As already stated, the face 6 may be secured to the cushion by glue or cement. If desired, the face 6 may be additionally secured by means such as wooden shoe-pegs 8, driven through the face into the cushion 5.

I claim—

1. A heel-finishing machine comprising an endless carrier of textile fabric adapted to engage and carry wax, means for supporting and moving said carrier, and means in frictional non-rotating engagement with said carrier, for heating and distributing the wax.

2. A heel-finishing machine comprising an endless carrier of textile fabric adapted to engage and carry wax, means for supporting and moving said carrier, and a wax heating and distributing shoe in non-rotating frictional wax-heating engagement with said carrier, and independent of the wax-supply.

3. A heel-finishing machine comprising an endless carrier of textile fabric adapted to engage and carry wax, means for supporting and moving said carrier, and a non-rotating wax heating and distributing shoe in frictional wax-heating engagement with said carrier, said shoe being limited in movement to a direction toward and from the carrier.

4. A heel-finishing machine comprising a plurality of supporting-rolls, one of which is provided with a yieldable surface, and a wax-carrier of wax-engaging textile fabric, formed as a belt movable upon the rolls.

5. A heel-finishing machine comprising a plurality of supporting-rolls, a support for one of the rolls, movable toward and from the companion roll and in a lateral direction, a wax-carrier formed as a belt movable upon the rolls, and a shoe mounted upon the said movable support and co-operating with the belt.

6. A heel-finishing machine comprising a plurality of supporting-rolls, a wax-carrier formed as a wax-engaging belt movable upon the rolls, and a non-rotary frictional shoe co-operating with the belt.

7. A heel-finishing machine comprising an endless carrier adapted to receive wax, means for supporting and moving said carrier, and a wax heating and distributing shoe in frictional contact with the carrier, said shoe having a rigid back, and a cushioned frictional face.

8. A heel-finishing machine comprising an endless carrier adapted to receive wax, means for supporting and moving said carrier, and a wax heating and distributing shoe in frictional contact with the carrier, said shoe having a rigid back, a cushion supported by said

back, and a leather friction-face supported by said cushion.

9. A heel-finishing machine comprising an endless carrier adapted to receive wax, means 5 for supporting and moving said carrier, a shoe-support adjacent to the carrier, a shoe adapted to bear on the wax-carrying face of the carrier, said shoe having a shank pivoted to the shoe-support to permit pressure-varying movements of the shoe, and adjustable 10 means for holding the shoe against the carrier.

10. A heel-finishing machine comprising a supporting-frame, a shaft journaled therein 15 and having a supporting-roll, a wax-carrier formed as a belt engaging said roll, an idle pulley engaging said belt, a support for said idle pulley, having a pivotal connection with the frame to permit a swinging adjustment of 20 the axis of the idle pulley, and means for se-

curing the said support to the frame in any position to which it may be adjusted.

11. A heel-finishing machine comprising a supporting-frame, a shaft journaled therein and having a supporting-roll, a wax-carrier 25 formed as a belt engaging said roll, an idle pulley engaging said belt, a bearing for the shaft of said pulley, a support for said bearing having a pivotal connection with the supporting-frame, the bearing having a sliding 30 connection with the support, and means for securing the bearing and support in any positions to which they may be adjusted.

In testimony whereof I have affixed my signature in presence of two witnesses.

JAMES E. JACKSON.
